The Hukoule refers to in these Letters Patent and making
part of the same containing a description in the words of the said
Sh. Ha. (Song) himself of his improvement in the construction of
Wooden or Iron Bridges.

The objects aimed at in this invention are greater
simplicity & economy in the construction of Bridges together
with greater strength & efficiency than had hitherto been ob-
tained from any combination of principles or arrangement of
parts hitherto adopted in Structures of this description.

The improvements under consideration by means of which the
objects above mentioned are to be accomplished consist of the
following Modifications or arrangements in the construction
of the main longitudinal truss frames necessary to the firm-
ation and support of a bridge viz. 1st Two modes of applying
the string pieces one of which is effected by means of wooden
to the other by means of iron splicing pieces, of a construction
different from any heretofore adopted in bridge manufacture
2nd A system of bracing by means of which the upper frames
are exempted from leverage in ^{any} part liable to be applied
by such an action. 3rd The shapes or thrusts communica-
ting by the braces are resisted by Shoulders or Steps and
nearly always be at right angles with the grain or fibers
of the timber & 4th A system of counter bracing by means
of which the truss frames are rendered stiff to withstand
the bridge kept in uniform action whether loaded
or unladen. 5th A mode of furnishing the main braces
and posts with metallic bearings by the introduction of
thin plates of iron, copper or other suitable metal between
the head of the upper main brace & the post in the first

against which they stand & 5" of made off, being or wedge
ing by means of which the central parts of the truss framed &
subsequently off, the bridge may be elevated and maintained
in case of a subsidence or sinking of those parts, which is
 liable to happen from a shrinkage and extraordinary
 compression of the timber. These several improvements which
 are claimed as new, useful and original together with
 a variety of other arrangements many of which are be-
 lieved to be unprecedented in bridge architecture
 will be more clearly illustrated by the drawings and ex-
 planatory references which are now exhibited under
the designation of the Victoria Bridge.

Explanations & References to the Drawings.

Plate I Fig. 1 A side view of the Truss Frame exhibiting
the system of bracing adulated to in articles 2 & 3 of the pre-
ceding specification. A. B. the upper string
showing the positions of its splices & the incisions of the parts
B. C. D. the lower string with its splices &c. Note inasmuch
as the upper string acts by thrust & has tension by tension, the splices
of the latter only require particular care & precision in their ad-
justment. E. F. Inferior check Braces supported on the lower
end of the abutment & inserted in the lower being immediately
behind the 2. & 3. posts from each extremity of the truss
frame. G. Superior arch braces connected with the center
post, prolonged above the Frame & inserted in the upper string
at the head of the 2. post from the center H. then Posts I. the
main braces. J. the counter braces. Note this figure is
also intended to indicate the manner of constructing the truss
frame, which differs only in its adaptation to the purpose
of a rail road, in which application the floor timbers will
be more frequent in order to afford unintermitting support to
the rails. The arrangements in other respects must be left

to admit the free & safe passage of a locomotive Steam Engine. The positions of clamp beams or floor timbers, attached to the girders by means of screw bolts. &c. The positions of intermediate floor timbers resting upon the main counter braces, at their junctions & intersections. Note The relative distances between the upper & lower strings & every two adjacent posts longitudinally of the Truss Frame should be about in the proportion of 1 $\frac{1}{2}$ to 1. Plate 1 Fig. 1. A horizontal view of all a bridge with single road way & double superstructures. Note The right half of this figure by B.C. G. R. presents a view of the lower strings. To one side is the left fig. of B.C.D. a view of the upper strings Beams lateral Braces &c. B.R. a horizontal mid way of the Bridge affording the means of connecting the lateral braces with the beams. a. the Beams. b. the lateral braces c. the splices of the upper (and lower strings) d. the splices of the intermediate string piece of the lower strings e. the floor timbers &c. lateral braces connected with the floor timbers g. a short staircase affording the means of connecting the braces e. with the floor timbers. Plate 2 Fig. 2. An end view of the timbers &c. of the Bridge AB may be used by men for maintaining the vertical position of the Truss Frames. C. the upper & D the lower sill of the abutment B. the transverse Braces. P the posts. a. the beams &c. the floor timbers Fig. 4. a. & b. to the same as in Fig. 3. Fig. 5 Representing a portion of the lower string with its own splicing pieces &c. a. the outside or exterior splicing pieces. b. the interior splicing pieces c. the spliced ends of the exterior string pieces d. the spliced ends of the interior string pieces. Fig. 6. a side view of the end of the interior splicing pieces showing the position of all transverse legs. Fig. 7 Representing a portion of the lower string with interior splicing pieces of wood a. the same as in Fig. 5. b. the exterior splicing piece which may be furnished with two corner blocks shouldered as in the figure, with four or with six shouldered according to the weight to be exerted upon it c. & d. the same as

in ~~the~~ ^{Note} The string pieces are confined together by means of screw holes, passing entirely thru the string at the head, & such other places as may be deemed necessary. The beams and floor timbers may also serve as clamps to the strings. Fig. 8 showing the manner in which the Potts the Maine Yawster braces the lower
